UNITED STATES PATENT OFFICE

CHARLES L. HILL, OF NORTH PLAINFIELD, NEW JERSEY, ASSIGNOR TO VENDEX, INC.,
OF NEW YORK, N. Y., A CORPORATION OF NEW YORK

COIN-CONTROL DEVICE

Application filed June 19, 1928. Serial No. 286,560.

This invention relates to coin-control mechanisms, and, more particularly, to coin-control mechanisms adapted for use in connection with vending machines.

5 An object of the invention is to provide a device of the type described which may be cheaply and easily manufactured and installed and which will operate in a positive manner and with freedom from mechanical 10 and operating defects during long periods of time.

A more specific object of the invention is to provide a coin-pawl bypass which will supplement the usual gravity action of the coin 15 positively to lift the pawl out of locking engagement with a stop upon operation of the machine to vend an article, and which, upon the return operation, will again act positively to return the pawl to locking engagement 20 with a stop.

Other objects of the invention will in part be obvious and will in part appear herein-after.

The invention accordingly comprises the 25 features of construction, combination of elements and arrangement of parts which will be exemplified in the construction hereinafter set forth, and the scope of the application of which will be indicated in the claims.

30 For a fuller understanding of the nature and objects of the invention reference should be had to the following detailed description taken in connection with the accompanying drawings, in which:

35 Figure 1 is a side elevational view of the device shown in normal position in relation to the coin chute;

Fig. 2 is a similar view of the device at the moment of approximate commencement of the vending operation;

Fig. 3 is a fragmentary view of the device during the return operation;

Fig. 4 is a fragmentary top plan view of the device; and

45 Figs. 5 and 6 are side and end elevations of the specific pawl-operating mechanism.

Although the device may be used in numerous connections, it is particularly adapted for use in connection with vending machines 50 of the type described and shown in United

States Letters Patent to C. W. Weeks, et al., No. 1,548,496, issued August 4, 1925, to which the device exemplifying the present invention may be applied in toto in substitution of and auxiliary to parts therein shown.

As is shown in Fig. 1, there is provided a coin chute 10 into which a coin or slug of suitable type is inserted prior to the vending operation of the machine. This chute delivers the coin onto the rear end 11 of a coin-pawl 12, which is suitably pivoted on the frame of the machine as at 13 and has its forward end 14 normally in engagement with a stop 15 of a cam 16. This cam is rotatably mounted upon a shaft 16', is adapted to be operated by a suitable lever or the like 17, and is operatively connected to the vending mechanism of the machine (not shown).

As will be readily understood, the coin-pawl 12 is so constructed and placed with respect to the pivot 13 that the forward end 14 normally rests in the position shown in Fig. 1, at which time operation of the machine is prevented. The gravity action of the pawl may, if desired, be supplemented by means of a coil-spring 18 attached to a pin 19 thereon and to the frame of the machine. Also, as is usual in a construction of such machines, the cam 16 is provided with a supplementary stop 20 which is somewhat higher than the stop 15 and acts to intercept the pawl 14 if and when a coin ejector (not shown) removes an improper slug from the rear end 11 of the coin pawl.

When, however, as is shown in Fig. 2, a coin or proper slug is resting on the end 11 of the coin pawl, the forward end 14 is raised to a position of clearance with respect to the stop 15.

In order to insure positive clearance of the stop 20 there is mounted upon the cam 16 a coin-pawl bypass 21 which is provided with a cam-portion 22, the forward end 22' of which curves downwardly toward the stop 15, and the end 14 of the coin-pawl 12 is equipped with a projection or pin 23, which, upon the forward or vending movement of the cam and coin-pawl bypass, rides over the end 22' of the cam-portion of the bypass. At this point the lever is checked by means

100

of the coil spring 18 and while in this position is not sufficiently depressed to permit the coin to be discharged from the chute 10.

The coin-pawl bypass 21 is also provided at its rear end with an upwardly-extending cam-portion 22', over which, during the continued forward movement of the cam 16, rides the pin 23 of the coin-pawl 12. The spring 18 is thereby stretched further and the end 11 of the lever is depressed sufficiently to permit discharge of the coin. Since the portion 22 of the coin-pawl bypass, in a preferred embodiment, is resilient in character, and the cam-portion 22' thereof projects somewhat higher than the supplementary stop 20, it will be depressed somewhat by the pin 23 during forward movement of the cam and, as shown in dotted lines in Fig. 2, will snap upwardly after the pin 23 is passed.

Upon the return movement of the cam 16 the pin 23 is again positively engaged by the coin-pawl bypass 22, this time, however, by the under side 24 thereof, and upon continued return movement of the cam the pin 23 passes out under the end 22' thereof and is again forced into locking engagement with the stop 15 of the cam.

It will thus be seen that by the structure an unauthorized vending action of the machine is effectually prevented and it is impossible, even by rapid manipulation of the machine, to obtain a second vending operation with the same coin.

Since certain changes may be made in the above construction, and different embodiments of the invention could be made, without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described and all statements of the scope of the invention which as a matter of language might be said to fall therebetween.

Having described my invention, what I claim as new and desire to secure by Letters Patent is:

1. A device of the type described, comprising, in combination, a movable cam having a pair of spaced stops, a gravity-controlled coin-pawl normally in engagement with one of said stops and adapted to be moved out of engagement therewith by the depositing of a coin thereon, a coin-pawl bypass associated with said cam and rearwardly of said first-mentioned stop, and means on the forward end of said coin-pawl for riding over said coin-pawl bypass positively to insure raising said coin-pawl out of engagement

with the other of said stops during the vending movement of said cam.

2. A device of the type described, comprising, in combination, a movable cam having a pair of spaced stops, a gravity-controlled coin-pawl normally in engagement with one of said stops and adapted to be moved out of engagement therewith by the depositing of a coin thereon, a coin-pawl bypass associated with said cam and rearwardly of said first-mentioned stop, and means on the forward end of said coin-pawl for coacting with said coin-pawl bypass positively to insure raising said coin-pawl out of engagement with the other of said stops during the vending movement of said cam; said last-mentioned means comprising a pin-member and said coin-pawl bypass having a forwardly- and downwardly-extending cam surface over which said pin-member rides upon movement of said cam.

3. A device of the type described, comprising, in combination, a movable cam having a pair of spaced stops, a gravity-controlled coin-pawl normally in engagement with one of said stops and adapted to be moved out of engagement therewith by the depositing of a coin thereon, a coin-pawl bypass associated with said cam and rearwardly of said first-mentioned stop, and means on the forward end of said coin-pawl for riding over said coin-pawl bypass positively to insure raising said coin-pawl out of engagement with the other of said stops during the vending movement of said cam and positively to return said coin-pawl into engagement with both of said stops upon the return movement of said cam.

4. A device of the type described, comprising, in combination, an oscillatable cam having a stop, a gravity-controlled coin-pawl normally in engagement with said stop and adapted to be moved out of engagement therewith by the depositing of a coin thereon, and a coin-pawl bypass associated with said cam and rearwardly of said stop; said coin-pawl bypass having a portion adapted to engage said coin-pawl upon the return movement of said cam after a vending operation positively to return said coin-pawl into engagement with said stop.

5. A device of the type described, comprising, in combination, a movable cam having a stop, a gravity-controlled coin-pawl normally in engagement with said stop and adapted to be moved out of engagement therewith by the depositing of a coin thereon, a coin-pawl bypass associated with said cam; said coin-pawl bypass having a resilient portion extending upwardly above said cam; and means on the forward end of said coin-pawl for riding over said resilient portion upon the vending movement of the cam; said resilient portion being adapted to snap upwardly after such action whereby upon the return

movement of the cam said means on said coin-pawl passes under said resilient portion of said coin-pawl bypass.

6. A device of the type described, comprising, in combination, a movable cam having a stop, a gravity-controlled coin-pawl normally in engagement with said stop and adapted to be moved out of engagement therewith by the depositing of a coin thereon, a coin-pawl bypass rigidly attached to the side of said cam and having its upper portion bent laterally to form a cam surface, said cam surface being resilient at its forward and rear ends and extending downwardly toward said stop at its front end and upwardly at its rear end; and a laterally-extending pin on said coin-pawl adapted to engage with the top of said cam surface on vending movement of said cam and to engage the underside of said cam surface during the return movement of said cam.

7. A device of the type described, comprising, in combination, a movable cam having a stop, a supplementary stop on said cam spaced from the first, a gravity-controlled coin-pawl normally in engagement with said stop and adapted to be moved out of engagement therewith by the depositing of a coin thereon, a coin-pawl bypass associated with said cam and rearwardly of said stop, and means on the forward end of said coin-pawl for riding over said coin-pawl bypass positively to insure raising said coin-pawl out of engagement with said supplementary stop during the vending movement of said cam and positively to return said coin-pawl into engagement with said stop upon the return movement of said coin.

In testimony whereof I affix my signature.

CHARLES L. HILL.
